CLAIM

I claim the ornamental design for a hat, as shown and described.

DESCRIPTION

FIG. 1 is a top plan view of a hat showing my new design; FIG. 2 is a front elevation view thereof;

FIG. 3 is a bottom plan view thereof;

FIG. 4 is a left side elevation view thereof;

FIG. 5 is a back elevation view thereof; and,

FIG. 6 is a right elevation side view thereof.

The broken lines shown in the drawings are stitching and form a part of the claimed design.
